(57) **CLAIM**

The ornamental design for an aluminum end snap-on plate, as shown and described.

DESCRIPTION

FIG. 1 is a perspective view of an aluminum end snap-on plate showing my new design;

FIG. 2 is a front view, the back view being identical thereof; FIG. 3 is a left side view, the right side view being identical thereof;

FIG. 4 is a top plan view thereof; and,

FIG. 5 is a bottom plan view thereof.

The broken lines shown in FIG. 2 are for illustrative purposes only and form no part of the overall claimed design.
